UNITED STATES PATENT OFFICE.

MILTON H. BALLARD, OF LYNN, MASSACHUSETTS, ASSIGNOR TO UNITED SHOE MACHINERY CORPORATION, OF PATERSON, NEW JERSEY, A CORPORATION OF NEW JERSEY.

PRESS.

Application filed March 13, 1920, Serial No. 365,399. Renewed March 17, 1922. Serial No. 544,686.

To all whom it may concern:

Be it known that I, MILTON H. BALLARD, a citizen of the United States, residing at Lynn, in the county of Essex and State of Massachusetts, have invented certain Improvements in Presses, of which the following description, in connection with the accompanying drawings, is a specification, like reference characters on the drawings indicating like parts in the several figures.

This invention relates to presses and more particularly to presses of the type employed in cutting out sheet material by the use of freely movable dies.

A well-known machine of the class referred to is the beam dinker which comprises characteristically a relatively long and narrow work supporting bed and a beam or cross-head which is reciprocable toward and from the bed in pressure applying operations. Commonly the beam in its upward position of rest is spaced from the bed a few inches only, a little more than the height of the largest die provided for use with the machine. The disadvantages of such a construction, for certain kinds of work, reside in the restricted space between the bed and the beam within which the die and the work must be manipulated and in the difficulty of seeing into this space to observe the characteristics of the work and to position the die properly with respect to the work. In other words, the beam in the construction described not only restricts the space within which manipulation of the die and work must take place but limits materially the amount of light which reaches the work. For work of such a character that plenty of light and space sufficient for accurate positioning of the die on the work are prime considerations, there has been used for many years a beam dinker wherein the beam is spaced a considerable distance from the bed and is provided with a presser member which is slidable along the beam into position over the die wherever located on the work. After each operation the presser member is pushed to one side while the die is being re-positioned on the work. As heretofore constructed these machines have proved to be far from satisfactory for a number of reasons. More particularly, the construction and arrangement of parts of these machines have been such as to permit without exception of a great deal of lost

motion between the presser member and its supporting beam so that very considerable backlash occurred during the operation of the machine which led to increased wear and occasionally to breakage of parts. Also deterioration of the connections between the presser member and its supporting beam was relatively rapid and this affected materially the ease with which the presser member could be shifted along the beam and rendered the force necessary to shift the presser member variable and uncertain.

Another factor which contributed to lower considerably the efficiency of these machines was the result of the ease, relatively speaking, with which the presser block could be shifted along the presser member since it imposed upon the operator the necessity of exerting force to stop the presser block in the desired position, otherwise the presser block would continue to move under its acquired momentum. This defect in the construction became manifest when the presser block was moved to one side to uncover the die after a presser applying operation. Commonly the operator shoved the block to one side and made no attempt to limit the extent of its movement to inoperative position with the result that the block moved much farther than necessary to uncover the die and had to be recovered at the expense of considerable effort on the part of the operator in repositioning it over the die preliminary to the succeeding cutting operation. Also in moving the presser block to operative position an appreciable effort had to be exerted in positioning the block over the die since its momentum tended to carry it beyond operative position.

It is an object of the invention to provide an improved press which will be free from the above-mentioned and other disadvantages and which will be especially simple in construction and efficient in operation.

In one aspect the invention comprises the provision in a press having relatively reciprocable presser members of a presser block mounted on one of said presser members and movable along said presser member into and out of position over the work in combination with means for taking up lost motion between the presser block and its supporting presser member, and prevent-

ing backlash, without in the least interfering with free movement of the presser block along its supporting presser member.

In another aspect the invention comprises 5 a press in which the movable presser member carries a presser block mounted for adjustment along the presser member, wherein connections between the presser block and presser member are so constructed and arranged as to maintain the presser block in 10 such relation to the presser member that lost motion between the block and member is reduced to the minimum.

In still another aspect the invention resides 15 in a press wherein the presser block is supported on the presser beam by means of flanges integral with or fixedly attached to the block in association with other connecting means between the block and beam comprising antifriction means which supports the block on the beam while the latter 20 is at rest.

In the illustrative embodiment of the invention the presser block is provided with 25 plates slidably mounted in the block in combination with spring means for supporting the block just out of contact with the under surface of the upper presser member.

Another object of the invention is to provide 30 improved means for assisting the operator to locate the presser block in operative position. In the illustrative construction this means comprises a brake under the control of the operator so that it may be released when the presser block is to be shifted to operative position and instantly applied again when the block reaches the desired position, thus relieving the operator of the necessity of exerting force to stop the block 35 in operative position as has heretofore been necessary. This same brake mechanism may also be used to bring the presser block to a stop after it has been moved to uncover the die and to prevent excess movement of the 40 presser block. In the illustrative embodiment of the invention the brake is mounted on the presser block and is arranged to be controlled by the same handle that is used to move the block along the presser member. 45 Moreover, the construction is preferably such that the brake is automatically applied when the handle is released by the operator.

Other features of the invention, together 50 with certain details of construction and combinations of parts, will be described in the specification and pointed out in the appended claims.

In the drawings:—

Fig. 1 is a front view illustrating one embodiment of the invention;

Fig. 2 is a perspective view partly in section of the presser block showing its connections with the supporting presser member;

Fig. 3 is a detail view of one of the anti-

friction rollers which support the presser block; and

Fig. 4 is a perspective view partly in section illustrating the preferred embodiment of the invention.

In the illustrative machine there is shown 70 a work supporting bed 4 supported adjustably on the frame 6 of the machine, adjustment of the bed being obtained through proper manipulation of adjusting members 8 according to a well known arrangement. For co-operation with the work supporting bed 4 in pressure applying operations

there is provided a cross-head or beam 10 mounted at each end upon a pair of rods 12 which are operatively connected at their lower ends to the main shaft 14 and are mounted in the frame for vertical reciprocation so as to carry the beam 10 toward and from the cutting bed 4 at each revolution 80 of the main shaft. Mounted on the said shaft is a power pulley 16, suitable clutch and brake mechanisms (not shown) being provided for connecting the power pulley to the shaft and disconnecting the same so that upon a single depression of the treadle 18, the shaft makes a single revolution and is then disconnected from the source of power. 90

During this revolution of the main shaft the presser beam 10 is moved toward the work supporting bed to operate upon the work and is then returned to its uppermost position as the position of rest. In the intervals of operation of the machine the work is properly positioned on the work supporting bed and the die located on the work in the desired relation. As shown, the beam 10 in its position of rest is spaced a considerable distance from the cutting bed 4 in order to provide room for manipulation of the work and of the die and space for access of all the light necessary for proper inspection of the work. Instead of moving the presser beam through the very considerable distance necessary for direct 100 co-operation with the bed there is provided a presser member or presser block 20 slidably mounted on the beam 10 so that it may be positioned over the die wherever the latter may be on the bed 4 to force the die through the work. After the beam is moved to its uppermost position, the presser block 20 may be readily moved toward one side, thus uncovering the die and the immediate 110 field of operations and providing space necessary for the manipulation of the work and the proper positioning of the die for the succeeding operation.

In the construction shown, the presser block 20 is provided with flanges 22 which engage other flanges 24 which provide guideways on each side of the cross-head 10. In the construction of the block and its flanges it is found as a practical matter that an appreciable space must be left between 120

the upper face of the flange 24 and the lower faces of the flanges 22 when the upper face of the block 20 is in contact with the lower surface of the beam 10, the said space 5 amounting ordinarily to $\frac{1}{16}$ of an inch. In the operation of the machine this amount of lost motion between the beam and the presser block would manifest itself by a very considerable backlashing that would develop 10 accompanied by an undesirable amount of jarring in the machine and lead to excessive wear of the parts and rapid deterioration of the machine as a whole. In order to obviate this objectionable feature 15 of the construction of prior machines, there is provided a supporting means for the block which will take up the lost motion between the block and the beam during upward movement of these parts and thus prevent 20 the backlashing that used to occur when the beam arrived at its upper position of rest. This is accomplished without in the least interfering with the ease with which the presser block may be shifted along the beam. In fact, the means referred to will 25 add to the ease with which the block may be moved since it will provide anti-friction rollers between the block and the beam as will be hereinafter described. As shown, 30 the said means for supporting the block 20 comprises two plates 26 one on each side of the block arranged to slide vertically in guideways 28 in the block and retained thereon for limited movement with respect 35 thereto by means of pins 30 which project from the block into slots 32 in the plate 26, the said pins being in the form of headed bolts with washers 34 interposed between the head of the bolt and the plate. At the 40 upper edge of each plate there is provided a plurality of bearings 36 each receiving the shaft 38 of a roller 40 arranged to engage the upper surface of the flange 24 on the beam 10. When the plates 26 are secured to the block 20 in proper adjustment thereto they will support the block on the flanges 24 so that the entire weight of the block is borne by the rollers 40, thus rendering 45 the lateral shifting of the block an easy operation for the operator. In the preferred construction, the plates 26 are so arranged as to support the block 20 through a spring means which, in the illustrative construction, comprises a bolt 42 securely 50 fixed to an extension 44 of the block 20 and extending upwardly through an opening in a corresponding abutment or extension 46 of the plate 26. Surrounding the bolt 42 and interposed between the projection 46 and the head of the bolt is a relatively heavy spring 48. It will be clear that adjustment 55 of the nut 50 will regulate the tension of the spring 48 and that these springs 48, one on each side of the block 20, support the block and that adjustment of the springs 60 can be made to hold the upper surface of the block 20 just out of contact with the under surface of the beam 10. With the block supported in the manner described there is practically no contacting of surfaces 65 between the block and the beam to produce friction and thus retard or resist shifting of the block along the beam. In other words, while the beam 10 is at rest, the block 20 is supported entirely from the anti-friction 70 rollers 40 which are so constructed as to reduce to a minimum the effects of friction between the supporting surfaces. Referring to the anti-friction rollers it is clear that any of the well-known constructions of such 75 rollers may be utilized in the present machine. As shown, each roller 40 is mounted on its shaft 38 with a ball race interposed between the roller and shaft, the said race consisting of annular plates 52 spaced from 80 each other and grooved to provide a race for the balls 54, the said annular plates being retained in the roller by means of a washer or disk 56 secured to the end of the 85 shaft 38.

An important feature of the construction resides in the provision of the flanges 22 as block supporting and guiding means. When the beam 10 starts upwardly at the 90 end of a pressure applying operation the block 20 is lifted by the flanges 22 thus relieving the rollers 40 and the roller bearings from the hammering that so soon results in deterioration and even breakage of these parts in prior machines. That the 95 flanges 22 sustain the greater part of the strain incident to overcoming the inertia of the block 20 during the first part of the upward movement is due to the yielding of the springs 48. However, as pointed out above, during the latter part of the upward movement, the springs lift the flanges 22 off of the flange 24 so that the rollers 40 support the block in such closed juxtaposition to the underside of the beam that no backlashing takes place when the beam comes 100 to rest at the end of its upward movement.

Mounted on the presser block 20 is a handle 58 for the convenience of the operator in shifting the block along the presser member or beam 10, the said handle comprising preferably a rod which extends practically the whole length of the block. Conveniently this handle is used to control a means for holding the block in the position to which it 105 has been moved by the operator. As stated in the foregoing description, presser blocks mounted on guideways through the interposition of anti-friction rolls are almost invariably moved beyond the desired location 110 because of the momentum of the block. Thus in the operation of the machine the operator must exert a certain amount of effort in stopping the presser block in the desired position above the die. Moreover, in 115

120

125

130

moving the presser block from above the work at the end of a pressure applying operation, the block is usually given a push that carries it further than is necessary to 5 uncover the work and hence it must be pulled back again through a greater space than should be necessary. To obviate this unnecessary waste of time and effort in positioning and re-positioning the presser 10 block, means is provided as stated for holding the presser block in the position to which it has been moved, the said means comprising, in the illustrative construction, 15 a brake mechanism arranged to be controlled by the handle for moving the presser block. As shown the brake mechanism comprises a plurality of friction blocks, one of which is illustrated at 60 (Fig. 2) mounted upon or integral with a plunger 62 vertically 20 slideable in the block 20 and urged upwardly by the spring 64. The construction is preferably such that downward movement of the handle 58 removes the brake which is again applied as soon as the handle is released 25 by the operator. In the illustrative construction the plungers 62 pass through openings in the form of slots in the arms 66 of the handle, the said arms being pivoted to the block as indicated at 63. It will be 30 clear that downward movement of the handle 58 will permit the brake members 60 to drop away from the lower surface of the beam 10 and that upon release of the handle the spring 64 will elevate the handle, and 35 perform the blocks 60, and carry the latter into frictional contact with the under surface of the beam, thus holding the block in the position to which it has been moved by the operator. It will be observed that the 40 mechanism is such as to automatically apply the brake whenever the operator lets go of the handle. In the illustrative device the plunger 62 has a lower reduced portion 70 which passes through the slot in the arm 66 and thus a shoulder is provided which engages the upper surface of the arm so that 45 the plunger is lifted to apply the brake on upward movement of the handle. If desired the upper surface of the brake members 60 may be roughened or provided with a friction pad or plate to ensure the requisite 50 braking action. While in the illustrative device the force of gravity is depended upon to move the brake members downwardly 55 when the handle is depressed it is obvious that spring means, for example, may be applied extending between the plunger 62 and the arm 66 to pull the brake members downwardly. 60 In the species shown in Figure 4 of the drawings a block 20 is mounted on the beam 10 for sliding movement along the flanges 24 of the beam by means of rollers 40 carried individually at the upper ends of plates 65 72 mounted for vertical sliding movement at each of the four corners of the block 20. As shown, the plate 72 is recessed at 74 to receive the upper portion of a bolt 76, the lower end of which is fixed to a face plate 78 which is securely attached to the block 20 by any well known means, that shown comprising a plurality of bolts 80 which pass clear through the block 20 and secure both plates 78 to the block. In the illustrative construction the plate 72 is provided with 70 an enlarged perforated portion 82 through which the bolt 76 passes and between the head of the bolt and the portion 82 there is located a relatively heavy spring 84 which can be readily tensioned by adjusting the 75 head of the bolt, an opening 86 being provided in the face plate 78 by which access may be had to adjust the head of the bolt. It will be understood that the tension of the 80 springs should be such as to support the block 20 just out of contact with the lower face of the beam 10 when the latter is at rest. Thus the block 20 is supported by the rollers 40 while the block is being adjusted along the beam, the under surfaces of the 85 flanges 88 being out of contact with the upper surface of the flange 24 during such sliding adjustment. It will be understood, however, that when the beam 10 starts upwardly after a pressure applying operation 90 the weight of the block 20 will be borne by the flanges 88 which are fixedly attached to or integral with the plates 78 on the block 20. Because of this construction the 95 rollers 40 are relieved of the danger of damage or breakage to which they would be subjected if they were forced to sustain the weight of the block 20 as the beam starts upwardly at the end of a pressure applying 100 operation. On the other hand, it is considered that the weight and tension of the 105 springs 84 are such that the rollers 40 are carrying the block 20 as the beam 10 approaches the upper limit of its movement in 110 such manner that the upper face of the block 20 is almost in contact with the lower face of the beam 10 and hence there will be very little if any jar and backslashing of the block 20 with respect to the beam 10 when the 115 latter comes to rest at the end of its upward movement. In the preferred construction 120 the rollers 40 are mounted upon stub shafts 90 carried in the upper ends of the plates 72, the said stub shafts having each a conical portion 92 located in the bearing in the plate 72 and so constructed and arranged that 125 wear on the bearings may be readily taken up by proper adjustment of the nut 94. Otherwise the rollers 40 are constructed as shown in Fig. 3 and as described earlier in this specification. 130

In order that the rollers 40 may yield laterally of the beam 10 when an unusual amount of lateral force is applied to the block 20 the plates 72 which carry the rollers

are mounted in the face plates 78 so that there is a certain amount of looseness or side play with respect to the upper ends of the plates, provision being made for taking up 5 yieldingly any tendency to lateral movement of the plates through spring means which comprises, in the construction shown, a plate or bar 96 which extends across the face of the plate 72 and projects into recesses 98 10 in the plate 78, which recesses loosely receive the ends of the bar 96. Mounted within a recess or chamber in the plate 78 is a spring 100 which presses upon the bar 96 and holds it yieldingly at one limit of its movement in 15 which the bar 96 retains the plate 72 yieldingly in normal position. If now the block 20, due to the stresses and strains to which the parts are subjected during the operation of the machine, should tend to move trans- 20 versely of the bar, the rollers 40 can yield with respect to the block 20 and thus escape damage since such lateral movement will be limited by the flanges 88 carried fix- 25 edly or integrally by the plates 78.

25 In this embodiment of the invention, the means for holding the block 20 in operative position and for holding the latter in in- 30 operative position at one side of the work comprises a braking means located between the rollers which normally support the block so that there is little or no tendency to tip the block on the bar when applying the braking means. Moreover, in this form of braking means the construction is such 35 that in releasing the brake there is no tendency to tip the block and thus disturb or interfere with its support by the anti-friction rollers. As shown the braking means comprises a brake member 102 having a friction surface or plate 104 designed to 40 contact with the upper surface of the flange 24 on the beam 10, the said member 102 being slidable vertically in a guideway in the plate 78. Connected to the member 102 is 45 a bolt 106 which passes slidably through spaced projections on the plate 78, a spring 108 being provided to urge the clamp member 102 downwardly into clamping relation with respect to the flange 24. In the construction shown the lower end of the bolt 50 106 carries a roller 110 to contact with a cam member 112 securely attached to a bar 114, the latter having a handle 116 and being pivoted practically at the center of the block 20 upon a pivot 118. As shown, the plate 78 has an opening 120 through which the bar 114 projects and along which it 55 may move as it is operated to move the cam 112 for the purpose of controlling the braking means. It will be understood that the cam 112 is in effect a double cam so arranged that when the roller 110 is contacting with the lowest part or intermediate portion of the double cam, the brake is applied. In other words the brake member 60 65 102 is pulled firmly down into contact with the flange 24 by means of the spring 108, when the handle 116 is in central or neutral position. To release the braking means the handle 116 may be moved in either direction, upon which movement the cam 112 operating on the roller 110 raises the braking member 102 and thus permits the block 20 to be slid freely along the beam support upon the anti-friction rollers 40. It will 70 be observed in releasing the brake in this form of the invention there is no tendency to tip the block on the beam and thus cause surfaces of the block other than the roller surfaces to contact with the beam and operate as braking means. The opening 120 above described has end walls which limit the movement of the bar 114 and thus of the handle 116 relatively to the block 20 so that movement of the handle 116 in either 75 80 direction first removes the brake and then causes the block 20 to move along with the handle. As soon as the operator ceases pulling on the handle 116, and this will occur when the block 20 has reached the desired 85 90 position over the die or has been moved to inoperative position at one side of the die, the said handle will be moved to its central position through the operation of the spring 108 which, by its expansive 95 pressure, causes the roller 110 to move the cam 112 and, therefore, the bar 114 until the roller reaches its lowermost position which is obviously when the bar 114 is practically at the center of the slot 120. In moving the block 20 by means of the handle 116, the latter is grasped by the operator and moved in the direction in which it is desired to move the block and this movement of the handle 116 at once releases the 100 105 braking means as above described.

In the operation of the machine the work is first positioned on the cutting bed 4 and the die located in proper location thereto after which the presser block is shifted into 110 position over the die and the pressure applying operation effected by tripping the clutch on actuation of the treadle 18. At the end of a single revolution the presser block is raised off of the work and can 115 then be shifted laterally in either direction to uncover the die so that the latter may be re-positioned on the work. In order that the presser block may be readily shifted by the operator a handle is attached to the 120 block in a position to be easily accessible to the operator.

Having thus described the invention, what is claimed as new and desired to be secured by Letters Patent of the United States is:—

1. In a machine of the class described, a work supporting bed, a reciprocable presser member having a guideway, in combination with a presser block slidably supported on 130

said guideway and movable along the under surface of the presser member, and means interposed between the presser member and block for taking up lost motion of the block and preventing backlash of the block during the operation of the machine.

2. In a machine of the class described, a work supporting bed, a presser member reciprocable toward and from said bed and provided with a guideway, in combination with a block slidable along the guideway so that it may be positioned over any desired portion of the bed, and means comprising a spring for taking up lost motion between the block and the presser member and for preventing backlash of the block during the operation of the machine.

3. In a machine of the class described, a work supporting bed, a presser member reciprocable toward and from the bed and provided with guiding flanges, in combination with a block for transmitting pressure between the presser member and the work on the bed, and means for supporting the block on said flanges comprising plates slidably mounted on said block, and spring means operating on the plates so as to hold the block just out of contact with the lower surface of the presser member and thus take up lost motion between the block and presser member.

4. In a machine of the class described, a work supporting bed, a presser member movable toward and from the bed and having guiding and supporting flanges, a presser block movable along the presser member to any desired position over the bed, comprising a block having flanges engaging over the flanges on the presser member, plates slidably mounted on said block and carrying rollers for supporting the block on the flanges of the presser member, and spring means interposed between the plates and the block for sustaining the block so that its upper face is supported just short of contact with the under surface of the presser member.

5. In a machine of the class described, a work supporting bed, a presser member reciprocable toward and from the bed and having guiding and supporting flanges on opposite edges thereof, a presser block slidably along the member into desired position over the bed comprising a block having flanges for engaging the flanges on the presser member, cheek plates slidably mounted on the block and carrying rollers for engaging the flanges of the presser member, means comprising pins for limiting the movement of the cheek plates on the block, and spring means interposed between the cheek plates and the block for supporting the block so that the upper face thereof is just out of contact with the lower face of the presser member.

6. In a machine of the class described, a work supporting bed, a presser member reciprocable toward and from the bed, a presser block slidably mounted on the presser member so that it may be positioned over the die wherever the latter may be located on the work, and yielding connections between the presser block and presser member for holding the presser block with its upper surface contiguous to the under surface of the presser member.

7. In a machine of the class described, a work supporting bed, a presser member reciprocable toward and from said bed and provided with a guideway, a block slidable along the guideway so that it may be positioned over any desired portion of the bed, a brake for holding the presser block in the position to which it has been moved by the operator, and manually operable means for moving the block and for controlling said brake.

8. In a machine of the class described, a work supporting bed, a presser member reciprocable toward and from said bed and provided with a guideway, a block slidable along the guideway so that it may be positioned over any desired portion of the bed, a brake for holding the presser block in the position to which it has been moved by the operator, and manually operable means for controlling said brake.

9. In a machine of the class described, a work supporting bed, a presser member reciprocable toward and from said bed and provided with a guideway, a block slidable along the guideway so that it may be positioned over any desired portion of the bed, a brake for holding the presser block in the position to which it has been moved by the operator and a handle for moving the presser block along the presser member and for controlling said brake.

10. In a machine of the class described, a work supporting bed, a presser member reciprocable toward and from said bed and provided with a guideway, a block slidable along the guideway so that it may be positioned over any desired portion of the bed, a brake for holding the presser block in the position to which it has been moved by the operator, and a handle for moving the presser block along the presser member, the construction and arrangement being such that movement of the handle in one direction releases the brake so that the presser block may be moved to the desired position, and means for automatically applying the brake as soon as the handle is released by the operator.

11. In a machine of the class described, a work supporting bed, a presser member reciprocable toward and from said bed and provided with a guideway, a block slidable along the guideway so that it may be posi-

tioned over any desired portion of the bed, a 5
brake mounted on the presser block for engagement with the presser member to hold the presser block in the position to which it has been moved by the operator, a handle 10
for moving the presser block along the presser member, connections between the handle and the brake for releasing the brake when it is desired to move the presser block, and spring means for returning the brake to operative position when the handle is released by the operator.

12. In a machine of the class described, a 15
presser member, a presser block slidable along the presser member, plates slidably mounted in the block on opposite sides thereof and carrying rollers at their upper ends for engagement with the presser member for supporting the block thereon, and flanges 20
fixedly secured to the block and arranged to engage over a surface on the presser member for picking up the block as the presser member starts upwardly after a pressure applying operation.

25 13. In a machine of the character described, a presser member, a block slidable along the presser member, connecting means between said block and presser member comprising anti-friction means for supporting the block for free movement along the presser member, and flanges carried fixedly by the block for engaging over a surface on the presser member so that said flanges support the block as the presser member starts 30
upwardly after a pressure applying operation.

35 14. In a machine of the class described, a presser member, a presser block slidable along the presser member, plates slidably 40
mounted in the block and carrying rollers at their upper ends for engagement with the presser member for supporting the block thereon, and flanges fixedly secured to the block between adjacent rollers and arranged 45
to engage over a surface on the presser member for taking the load of the block during upward movement of the presser member.

50 15. In a machine of the character described, a presser member, a block slidable along the presser member, a plate mounted in the block, means for yieldingly connecting the plate to the block for movement therein in directions angularly related to each other and anti-friction means supported by said plate for connecting the block 55
slidably to the presser member.

16. In a machine of the character described, a presser member, a block slidable along the presser member, a plate mounted 60
in the block, spring means for connecting the plate to the block so that the plate may move vertically in the block under the control of the spring means, and other spring means for holding the plate in normal position in the block and yieldable to permit the

plate to move laterally with respect to the block.

17. In a machine of the character described, a presser member, a block slidable 70
along the presser member, supporting members on the block for engaging the presser member, and braking means for holding the block in position to which it has been moved by the operator comprising a brake member carried by the block and located between adjacent supporting members on the block.

18. In a machine of the character described, a presser member, a block slidable along the presser member, and braking 80
means for holding the block in the position to which it has been moved by the operator comprising a brake member arranged to extend over a surface on the presser member frictionally to engage said surface to hold the block in the selected position.

19. In a machine of the character described, a presser member, a block movable 85
along the presser member, and braking means for holding the block in the desired position on the presser member comprising a brake member, and means movable selectively in the directions of the back and forth movements of the block for releasing said brake member.

20. In a machine of the character described, a presser member, a block movable along the presser member, and braking 90
means for holding the block in the desired position on the presser member comprising a brake member, and a single means movable in the direction of movement of the block in both of the back and forth movements of the latter for moving the block 95
and for controlling the brake member.

21. In a machine of the character described, a presser member, a block slidable along the presser member, a braking means 100
for holding the block in the desired position on the presser member, and a single means for applying and releasing the braking 105
means comprising a member movable in the direction of movement of the block in both of the back and forth movements of the latter for releasing the braking means and for then moving the block along the presser member.

22. In a machine of the character described, a presser member, a block slidable along the presser member, a braking member mounted in the block and arranged to 110
engage a surface on the presser member to hold the block in the desired position, a handle member for moving the block selectively in opposite directions along the presser member, and connections between the handle member and the brake for releasing the brake as the handle member is moved in a direction parallel to the path of the block.

23. In a machine of the character de- 115
120
125
130

- scribed, a presser member, a block slideable on the presser member, and braking means for holding the block in the desired position on the presser member comprising a 5 brake member designed to engage an upwardly facing surface on the presser member, means for causing the brake member to engage said surface, a handle member for moving the block selectively in opposite directions along the presser member, and connections between said handle member and the brake member for releasing the brake before the handle can operate to move the block.
- 10 24. In a machine of the character described, a presser member, a block slideable along the presser member, and braking means for holding the block in the desired 15 position on the presser member comprising a brake member, spring means for applying the brake member, and a handle member movable in the block for releasing the brake member and operative thereafter for moving the block selectively in a plurality of directions along the presser member.
- 20 25. In a machine of the character described, a presser member, a block movable along the presser member, and braking means for holding the block in the desired 25 position on the presser member comprising a brake member for engaging over a surface on the presser member, spring means for applying the braking member yieldingly to the presser member, a cam for controlling the brake member and a handle member for operating the cam member and for thereafter moving the block.
- 30 26. In a machine of the character described, a presser member, a block slideable along the presser member, and braking means for holding the block in the desired 35 position on the presser member comprising a braking member constructed and arranged to engage an upwardly facing surface on the presser member, spring means for holding the braking member in frictional contact with said surface on the presser member, a cam for controlling the braking member, and a handle member carrying said 40 cam and movable to operate the cam and thereafter to move the block along the presser member.
- 45 27. In a machine of the character described, a presser member, a block movable along the presser member, and braking means for holding the block in the desired 50 position on the presser member comprising a braking member, spring means for applying the brake member to the presser member, a double cam for moving the braking member to inoperative position, and a handle member carrying said cam and movable to cause the cam to operate the brake member, the spring means and the cam being cooperative to cause the re-application of the 55
- braking member and the return of the handle to initial position.
- 60 28. In a machine of the class described, a work supporting bed, a presser member movable toward and from the bed in pressure applying operations, a block slideable along the presser member, and means for holding the block against movement lengthwise of the presser member and in a position which may be determined solely with 70 reference to work located on the work supporting bed.
- 65 29. In a machine of the class described, a work supporting bed, a member extending longitudinally of the bed and above the same, and a presser block movable along the member to positions which may be selected solely with reference to the work on the work supporting bed, and means for holding the block in the selected position.
- 75 30. In a machine of the class described, a work supporting bed, a member extending longitudinally of the bed and above the same, a presser block movable along the member so as to be positioned solely with 80 reference to the work on the work supporting bed, means for holding the block in the selected position, and a manually operable member for moving the block and for controlling said means.
- 85 31. In a machine of the class described, a work supporting bed, a member extending longitudinally above the bed, a presser block movable along said member into and out of operative relation to the work on the work supporting bed, means rigidly connected to the block for supporting the presser block during certain periods in each 90 cycle of operations of the machine, and spring means for supporting the block 95 while the latter is at rest.
- 90 32. In a machine of the class described, a work supporting bed, a member extending longitudinally above the bed, a presser block movable along said member to the desired operative position, a manually operable member for moving the block and having a yielding connection with the block, and means for returning the manually operable member to its initial position when 100 released by the operator.
- 100 33. In a machine of the class described, a work supporting bed, a member extending longitudinally above the bed, a presser block movable along the member to selected 105 position above the work, means for holding the block in the position to which it has been moved by the operator, a manually operable member for controlling said means and for moving the block in either direction over the bed, and means for holding the manually operable member yieldingly 110 in its normal position of rest.
- 110 34. In a machine of the class described, two presser members relatively movable to- 115
- 120
- 125
- 130

ward and from each other in pressure applying operations, and a presser block movable along the pressure applying face of one of the presser members to positions which may be selected solely with reference to work placed between the presser members, and means for holding the block in selected position.

35. In a machine of the class described, 10 a work supporting bed, a member extending across the bed in spaced relation thereto, a presser block movable along the member so as to be positioned with respect to work located on the bed, interlocking means 15 between the block and the member constructed and arranged to support the block during movement of the member in one direction, and spring means for supporting the block on the member while the member 20 is at rest.

36. In a machine of the class described, a work supporting bed, a member extending across the bed in spaced relation thereto, and a presser block movable along the 25 member and into and out of operative relation to work on the work supporting bed, the said member having supporting flanges for the presser block, and the block having co-operating flanges designed for direct connection with the supporting flanges of the member 30 whereby a strong and durable connection is provided between the presser block and the supporting member.

37. In a machine of the class described, 35 a work supporting bed, a member extending longitudinally above the bed in spaced relation thereto, a presser block movable along said member and into and out of operative relation with respect to work on the work supporting bed, and supporting 40 rollers for the presser block yieldingly connected to the block.

38. In a machine of the character described, a work supporting bed, a member 45 extending longitudinally across the bed in spaced relation thereto, a presser block movable along the member and into and out of operative relation to work supported on the work supporting bed, and friction means for holding the block in the desired relation 50 with respect to the work on the bed.

39. In a machine of the character described, a work supporting bed, a member extending longitudinally across the bed in spaced relation thereto, a presser block movable along the member and into and out of operative relation to work supported on the work supporting bed, and manually operable means for moving the block along its 55 supporting member and for holding the block in a position which may be selected solely with respect to work on the work supporting bed.

40. In a machine of the character described, a work supporting bed, a member

extending longitudinally above the bed, a presser block movable along the member and into and out of operative relation to work on the work supporting bed, said block being so mounted as to have its operative face 70 maintained constantly in parallelism with the upper surface of the work supporting bed, means for operating the presser block toward and from the bed to apply pressure on the work, and a handle extending laterally from the block in a position accessible to the operator for controlling the movements of the block in all directions relatively to its supporting member.

41. In a machine of the class described, 80 two presser members relatively movable toward and from each other, a presser block supported on one of the members for movement into and out of operative relation with respect to work located between the members, means for holding the block in selected operative position with respect to the work, means for causing a pressure applying operation of the block upon the work, and a 85 single manually operable member for moving the presser block in either direction along its supporting member.

42. In a machine of the class described, 90 two presser members relatively movable toward and from each other, a presser block supported on one of the members for movement into and out of operative relation with respect to work located between the members, means for causing a pressure applying 95 operation of the block upon the work, and plates yieldingly connected to the presser block and provided with rollers for rotatably engaging with the supporting member for the block, said block having flanges for rigidly engaging with the supporting member for the block during relative movement 100 of the presser members away from each other.

43. In a machine of the class described, 110 a work supporting bed, a member extending longitudinally above the bed, a presser block movable along said member and into and out of operative relation to work on the work supporting bed, interlocking means between the block and its supporting member constructed to hold the block on the member while permitting sliding movement of the block with respect to its supporting member, locking means for ensuring the retention of the presser block in selected operative position on its supporting member, and means normally operative to facilitate movement of the presser block along its supporting member while the latter is at rest.

44. In a machine of the class described, 115 a work supporting bed, a member extending longitudinally above the bed, a presser block movable along said member and into and out of operative relation to work on the work supporting bed, interlocking means 120

between the block and its supporting member to support the former on the latter constructed to permit sliding movement of the block with respect to its supporting member, locking means for ensuring the retention of the presser block in selected operative position on its supporting member, and an anti-friction means for supporting the

presser block on its supporting member while the latter is at rest so constructed and arranged as to facilitate relative movement between the block and its supporting member. 10

In testimony whereof I have signed my name to this specification.

, MILTON H. BALLARD.
